(57) **CLAIM**

I claim the ornamental design for a composite siding, as shown and described.

DESCRIPTION

FIG. 1—is a left side view of a composite siding thereof; FIG. 2—is a back view of a composite siding thereof; FIG. 3—is a right side view of a composite siding thereof; FIG. 4—is a front view of a composite siding thereof; FIG. 5—is a top view of a composite siding thereof; FIG. 6—is a bottom view of a composite siding thereof; FIG. 7—is a back perspective view of a composite siding thereof; FIG. 8—is a side perspective view of a composite siding thereof; and, FIG. 9—is a front perspective view of a composite siding thereof.

The broken lines showing the joint configuration between element are for illustrative purposes only and form no part of the claimed design.
